Attorney, Agent, or Firm—Quarles & Brady LLP

CLAIM

An ornamental design for a modular hot beverage brewing device face plate, as shown and described.

DESCRIPTION

FIG. 1 is a front elevation;

FIG. 2 is a left side elevation;

FIG. 3 is a right side elevation;

FIG. 4 is a top plan; and,

FIG. 5 is a bottom plan.

The broken line showing of the housing portion of the beverage brewing device in FIGS. 2-4 is for illustrative purposes only and forms no part of the claimed design.
